CONVERSION OF HYDROCARBONS

Karl J. Korpi, Beacon, N. Y., assignor to The Texas Company, New York, N. Y., a corporation of Delaware

Application August 7, 1942, Serial No. 453,976

8 Claims. (Cl. 196—52)

This invention relates to the conversion of hydrocarbons and has to do particularly with conversion into lower boiling products such as gasoline in the presence of a catalyst.

In accordance with the invention the hydrocarbon feed oil is subjected while at elevated temperature to the action of a cracking catalyst which is in a high state of activity such that substantial conversion of feed hydrocarbons into gasoline hydrocarbons occurs. The catalyst is not maintained in contact with feed oil undergoing conversion sufficiently long to become completely spent or even substantially spent. Instead, the partially spent catalyst still of relatively high activity is employed as a reforming catalyst under substantially different operating conditions to treat the gasoline hydrocarbons formed by cracking during contact between feed oil and the catalyst in its more active state.

The term reforming is used in a generic sense as involving reactions of isomerization and polymerization, as well as hydrogen transfer wherein naphthene hydrocarbons are converted to aromatics and hydrogen and the resulting hydrogen is utilized to combine with olefins formed from the conversion of other constituents of the hydrocarbon mixture undergoing treatment.

More specifically the invention comprises cracking higher boiling hydrocarbons such as kerosene, gas oil and the like by the action of an active cracking catalyst at a temperature above about 900° F. and which may range from about 1000 to 1200° F. The heated oil in vapor phase and under low pressure is maintained in brief contact with the catalyst, as for example, for about a second or less, the total time that the catalyst is maintained in contact with hydrocarbons under these conditions of high temperature being in the range about 1 to 2 minutes and not in excess of about 5 minutes. The catalyst is thus only partially spent so far as concerns its effectiveness as a cracking catalyst.

The hydrocarbon products of the conversion reaction are fractionated to remove gasoline hydrocarbons or a fraction consisting essentially of gasoline hydrocarbons. This gasoline, or any desired portion thereof, is separately subjected to the action of the partially spent catalyst under less drastic temperature conditions so as to effect reforming of the gasoline hydrocarbons. The partially spent catalyst is employed directly in the reforming step without an intervening reactivation to remove carbonaceous and other material adhering to it as it issues from the cracking operation.

This reforming treatment is advantageously effected at a temperature ranging from 700 to 900° F. with a contact time between hydrocarbons and catalyst of about 1 to 20 seconds. In this case, the total time that the catalyst is maintained in contact with gasoline hydrocarbons undergoing treatment ranges from about 5 to 30 minutes.

Substantially atmospheric pressure may prevail in both conversion operations although pressures substantially below atmospheric may be used.

The process is advantageously practiced by employing a finely divided or powdered type of catalyst which is passed from the cracking reaction to the reforming or secondary reaction zone in substantially continuous flow. In such type of operation fresh or freshly regenerated catalyst and feed hydrocarbon are charged continuously to a cracking reaction zone, the powdered catalyst being suspended in the body of hydrocarbon vapor passing through the reaction zone, or if desired being in the form of a moving bed.

The catalyst is continuously withdrawn from the cracking reaction zone so that the residence time of the catalyst within the reaction zone will not exceed several minutes. The withdrawn catalyst, without reactivation, is passed to the reforming reaction zone, wherein it may be employed in substantially the same manner as in the cracking reaction zone. The catalyst is continuously drawn off from the reforming reaction zone and passed to regenerating means wherein the carbonaceous deposit upon the catalyst is removed by burning under properly controlled conditions so as not to injure the particle structure or in other words, so as to avoid destroying its catalytic activity.

The catalyst may be either a naturally occurring or synthetic adsorbent solid material. Siliceous adsorbent material such as active clays and zeolites are contemplated. Activated clays useful for this purpose include acid treated bentonites, such as Filtrol. Synthetic catalysts of inorganic gel-type such as alumina-silica, with or without the addition of metal oxides such as zirconium or molybdenum oxide, may be used. In general a catalyst is employed which is stable at high temperatures, of the order of 1400 to 1600° F. as determined by calcining in a muffle furnace at that temperature, and which is a measure or indication of the ability of the catalyst to maintain its activity under the customary temperatures of reactivation in the range 1100 to 1400° F. It is pre-

ferred to employ a catalyst which is substantially free from alkali and alkali-earth metals.

It is thought that catalytic cracking involves adsorption of a molecular film of hydrocarbon on the active centers of the catalyst followed by desorption of this film accompanied by cracking. The heat of adsorption of the oil on the catalyst provides energy of activation. The indications are that adsorption with its activating influence precedes cracking.

The initially adsorbed film on the catalyst proceeds to crack, polymerize and form carbon. It appears that the molecular weight of the adsorbed film decreases with increasing temperature, approaching that of carbon as a limit in the neighborhood of 950° F. and above. The molecular weight also increases with the residence time of the catalyst in the reaction zone. Moreover, the cracking or desorption pressure apparently decreases rapidly as catalyst residence time is lengthened and also as pressure is applied.

Accordingly, the present invention involves effecting the cracking step under high temperature and low pressure with relatively short exposure of both oil and catalyst to the conversion conditions so as to reduce the molecular weight of the adsorbed film and thereby secure a high conversion to high grade gasoline with reduction in carbon formation. The use of a high velocity of inert carrier gas through the reaction zone may be resorted to as a means of reducing the effective pressure.

By operating with a short catalyst residence time within the reaction zone the catalyst is at a high average level of activity during the entire period that it is within the reaction zone and this is advantageous from the standpoint of producing high octane gasoline having a high lead susceptibility. It appears that catalytic conversion under these conditions favors the hydrogen transfer reaction to which reference has already been made.

As already mentioned the second or reforming step of the process is also carried out under conditions to favor the further extension of the hydrogen transfer reaction. The reforming operation also effects polymerization of unsaturated constituents of the gasoline which would otherwise result in increasing the acid heat value of the final product. In addition, the reforming operation involves increasing the branched chain character of aliphatic hydrocarbons including both olefins and paraffins. The product obtained is of increased octane value and possesses greater lead susceptibility.

Reference will now be made to the accompanying drawing illustrating diagrammatically one method by which the invention may be practiced.

Feed oil such as gas oil is drawn from a source not shown and conducted through a pipe 1 to a heater 2 wherein the oil is rapidly heated to a cracking temperature but without substantial cracking occurring. This temperature may be in the range 900 and above and may, for example, be 1000 to 1200° F.

The heated oil vapors are conducted through a pipe 3 to a reactor 4 wherein the hydrocarbon vapors are subjected to the action of a catalyst. It is desirable that pyrolytic cracking be substantially avoided prior to contact between the hydrocarbons and the catalyst.

The reactor 4 is advantageously of the type in which a powdered type of catalyst is employed

using a high ratio of catalyst to hydrocarbon as, for example, up to 10 to 15 parts by weight of catalyst to 1 part of feed hydrocarbon.

A relatively large mass of catalyst may be maintained in the form of a fluid suspension within the reactor.

The catalyst powder may be introduced from a conduit 5 to the reactor along with the feed hydrocarbon stream using the hydrocarbons as an injecting medium. Catalyst is continuously removed from the reactor. The bulk of it may be discharged from the bottom of the reactor through a conduit 6 or instead, the bulk of it may be discharged along with the hydrocarbon vapors through a conduit 7, depending upon the conditions of operation employed. Catalyst may be discharged simultaneously through both conduits 6 and 7.

By operating with a high velocity of hydrocarbon and catalyst powder through the reactor so that substantially all of the catalyst is carried out through the conduit 7, the residence time of the catalyst within the reactor can be maintained not in excess of about 2 to 5 minutes, while the residence time of the hydrocarbon vapors within the reactor will be materially less, in the order of 1 or 2 seconds.

The effluent stream of hydrocarbons and catalyst is discharged through the conduit 7 to a separator 8 providing means for separating the entrained catalyst from the hydrocarbon vapors.

The hydrocarbon vapors comprising gaseous hydrocarbons, gasoline hydrocarbons and higher boiling hydrocarbons are conducted from the separator through a conduit 9 leading to a fractionator 10.

The fractionator 10 is advantageously operated so as to separate gasoline and lighter hydrocarbons from the higher boiling hydrocarbons which latter are discharged from the bottom thereof through a conduit 11. The gasoline and lighter hydrocarbons are removed as a distillate through the conduit 12 leading to a second fractionator or stabilizer 13 wherein gaseous hydrocarbons are removed as an overhead fraction through a conduit 14 while the gasoline hydrocarbon fraction is removed from the lower portion of the fractionator 13 through a conduit 14a.

If desired, the fractionation in the fractionator 13 may be omitted; in which case the distillate passing through the conduit 12 will be bypassed through a branch conduit 15 leading to a heater or heat exchanger 16.

The gasoline hydrocarbons leaving the heater 16 advantageously in vapor form and heated to the desired temperature are passed through a conduit 17. The conduit 17 communicates with a conduit 18 affording communication between the separator 8 and the lower portion of a reactor 19 wherein the gasoline hydrocarbons are subjected to the reforming reaction. Thus, the gasoline hydrocarbons together with partially spent catalyst from the separator 8 are continuously passed to the reactor 19.

The partially spent catalyst withdrawn from the separator 8 may be at sufficiently high temperature so that it is unnecessary to add heat to the gasoline hydrocarbons passing to the reactor 19. In such case the previously mentioned heater 16 may be bypassed as indicated in the drawing. If necessary a portion of the hydrocarbons may bypass the heater 16 in order to control the temperature maintained in the reactor 19, which temperature is advantageously in the range about 700 to 900° F.

The reactor 19 may be similar in design and operation to the reactor 4 except that the conditions of flow therethrough are such as to maintain the desired conditions of catalyst and hydrocarbon residence time within the reaction zone. Thus, the catalyst and hydrocarbons may remain in contact within the reactor for a period of 1 to 20 seconds while the residence time of the catalyst may range from 5 to 30 minutes.

The effluent hydrocarbons together with entrained catalyst powder are removed from the top of the reactor through a conduit 20 leading to a separator 21 substantially similar to the separator 8 previously referred to. The hydrocarbons substantially free from catalyst powder are conducted from the separator 21 through a conduit 22 leading to a fractionator 23. The fractionator 23 may be operated so as to effect fractionation into any desired number of fractions. For example, a distillate fraction consisting essentially of gaseous hydrocarbons may be removed and discharged through a conduit 24 while a gasoline fraction may be separated and discharged through a conduit 25, the higher boiling hydrocarbons being discharged from the lower portion of the fractionator through a conduit 26.

That portion of the catalyst separated in the separator 21 may be recycled through the reactor 19 and in such case it is passed through a conduit 27 which communicates with the previously mentioned conduit 18. Instead of recycling this catalyst to the reactor 19 it may be drawn off and reactivated following which it can be recycled to the reactor 4.

The spent catalyst discharged from the reactor 19 either through conduit 27 and branch conduit 28 or through conduit 29, is passed to a reactivation unit 30 wherein the carbonaceous deposit upon the catalyst particles is removed by burning. Since the reactivation of conversion catalysts of this type is now well understood it is deemed unnecessary to describe the operation of the reactivation unit 30 in detail.

The reactivated catalyst is passed from the unit 30 through the previously mentioned conduit 5 by which means it is returned to the reactor 4 for contact with the fresh feed oil.

As already intimated in the operation of the reactor 4 some or substantially all of the catalyst may be discharged through the conduit 6. In this case the partially spent catalyst may pass from the conduit 6 through a branch conduit 31 which communicates with the previously mentioned conduit 18 and in this way is conveyed to the reactor 19.

In the event that all of the partially spent catalyst drawn off from the reactor 4 is not passed to the reactor 19 the remainder may then be passed directly to the reactivation unit 30.

While mention has been made of using reactors in which the catalyst is employed in a suspended form, nevertheless it is contemplated that other types of reactors may be employed as, for example, wherein the catalyst passes through the reactor in the form of a continuously moving bed. In such case the catalyst bed may move either countercurrently to or concurrently with the stream of hydrocarbons undergoing conversion.

Vertical reaction vessels may be employed in which both hydrocarbon vapors and catalyst particles pass downwardly through the vessel in concurrent flow. On the other hand, the arrangement may be such that the catalyst particles flow or pass through the reactor in a vertical direction while the hydrocarbons flow in a horizontal or

substantially horizontal direction. By proper selection of the rate and direction of flow of hydrocarbons and catalyst, as well as shape and dimensions of the reaction vessel, the desired conditions of hydrocarbon and catalyst residence times may be maintained.

Both the cracking and reforming reactions may be carried out in the presence of added gaseous hydrocarbons including hydrogen and hydrogen-containing gases such as methane, ethane, etc. Also if desired the gaseous fractions removed from the fractionators 13 and 23 may be recycled through the reactors 4 and 19 for the purpose of supplying the added gaseous agents or diluents.

The addition of these and other gaseous agents is beneficial in aiding volatilization of heavy polymer material which otherwise tends to remain adhering to the catalyst and is ultimately converted to carbonaceous deposit.

Other agents useful in displacing carbon-forming bodies from the catalyst or in inhibiting their deposition thereon may include carbon monoxide, carbon dioxide, sulfur dioxide, carbonyl sulfide, metal carbonyls, etc.

Obviously many modifications and variations of the invention, as hereinbefore set forth, may be made without departing from the spirit and scope thereof and therefore only such limitations should be imposed as are indicated in the appended claims.

I claim:

1. A process for the catalytic conversion of hydrocarbons to produce gasoline which comprises passing feed oil higher boiling than gasoline to a catalytic reaction zone, subjecting the oil therein to the action of an active cracking catalyst in solid granular form under conditions of elevated temperature such that substantial conversion of higher boiling hydrocarbons into gasoline hydrocarbons occurs, obtaining from said catalytic cracking reaction a cracked hydrocarbon mixture containing gasoline hydrocarbons and hydrocarbons higher boiling than gasoline, also obtaining from said reaction partially spent catalyst which has been in contact with feed oil in said reaction zone for not in excess of about 5 minutes between reactivations and which is at elevated temperature, separating gasoline hydrocarbons from said hydrocarbon mixture and separately subjecting said gasoline hydrocarbons to the action of said partially spent catalyst, without intervening reactivation and without substantial cooling of the catalyst under less drastic temperature conditions than prevail in the cracking zone such that substantial reforming of the gasoline hydrocarbons is secured.

2. A process for the catalytic conversion of hydrocarbons to produce gasoline which comprises passing feed oil higher boiling than gasoline to a catalytic reaction zone, subjecting the oil therein to the action of an active cracking catalyst in solid granular form under conditions of elevated temperature such that substantial conversion of higher boiling hydrocarbons into gasoline hydrocarbons occurs, obtaining from said catalytic cracking reaction a cracked hydrocarbon mixture containing gasoline hydrocarbons and hydrocarbons higher boiling than gasoline, also obtaining from said reaction partially spent catalyst which has been in contact with feed oil in said reaction zone for not in excess of about 5 minutes between reactivations and which is at elevated temperature, separating gasoline

hydrocarbons from said hydrocarbon mixture, separately subjecting said gasoline hydrocarbons to the action of said partially spent catalyst, without intervening reactivation and without substantial cooling of the catalyst, under less drastic temperature conditions than prevail in the cracking zone such that substantial reforming of the gasoline hydrocarbons is secured, withdrawing catalyst used in said reforming, reactivating said withdrawn catalyst and recycling reactivated catalyst to the cracking reaction zone.

3. The method according to claim 1 in which the cracking reaction is effected at a temperature in the range 900 to 1200° F. and the reforming reaction is carried out at a temperature in the range about 700 to 900° F.

4. A continuous process for the catalytic conversion of hydrocarbons which comprises passing a stream of feed hydrocarbon higher boiling than gasoline to a cracking reaction zone, passing an active cracking catalyst in solid granular form to said zone, subjecting the feed hydrocarbon to brief contact with said catalyst within the reaction zone such that substantial conversion of higher boiling hydrocarbons into gasoline hydrocarbons occurs, continuously removing the partially spent catalyst and reacted hydrocarbons from said zone, said removed catalyst having been in contact with feed oil in the reaction zone for not in excess of about 5 minutes between reactivations and being at an elevated temperature, separating gasoline hydrocarbons from said reacted hydrocarbons, passing said gasoline hydrocarbons through a reforming zone, subjecting the gasoline hydrocarbons therein to the action of said partially spent catalyst, without intervening reactivation and without substantial cooling of the catalyst under less drastic temperature conditions than prevail in the cracking zone such that substantial reforming of the gasoline hydrocarbons is secured and withdrawing converted gasoline hydrocarbons and spent catalyst from the reforming reaction zone.

5. The method according to claim 4 in which

the cracking reaction is effected at a temperature in the range about 900 to 1200° F. and the reforming reaction is effected at a temperature in the range about 700 to 900° F.

6. A continuous process for the catalytic conversion of hydrocarbons which comprises passing a stream of feed hydrocarbon higher boiling than gasoline to a cracking reaction zone, passing an active cracking catalyst in solid granular form to said zone, maintaining hydrocarbons and catalyst within the reaction zone at a temperature in the range about 900 to 1200° F., the time of contact between hydrocarbons and catalyst being of the order of about one second, removing partially spent catalyst and reacted hydrocarbon mixture from said zone, said removed catalyst having been in contact with feed oil in the reaction zone for not in excess of about 5 minutes between reactivations and being at an elevated temperature separating gasoline hydrocarbons from said hydrocarbon mixture, passing said gasoline hydrocarbons to a reforming zone, passing said partially spent catalyst without intervening reactivation and without substantial reduction in temperature to said reforming zone, maintaining the gasoline hydrocarbons and partially spent catalyst within the reaction zone at a temperature in the range about 700 to 900° F., the time of contact between gasoline hydrocarbons and catalyst being in the range about 1 to 20 seconds and withdrawing converted gasoline hydrocarbons and spent catalyst from the reforming reaction zone.

7. The method according to claim 6 in which the spent catalyst withdrawn from the reforming zone is reactivated and recycled at least in part to the cracking zone.

8. The method according to claim 6 in which the residence time of the catalyst in the cracking reaction zone is about 1 to 2 minutes and the residence time of the partially spent catalyst in the reforming zone is in the range about 5 to 30 minutes.

KARL J. KORPI.
